SUPPORT FOR MOTION-PICTURE APPARATUS AND THE LIKE

Andre Victor Leon Clement Debrie, Paris, France

Application February 23, 1950, Serial No. 145,644
In France April 7, 1949

13 Claims. Cl. 95—86)

1

This invention relates to supports for motion picture apparatus and the like.

Motion picture apparatus, more particularly projection apparatus, is usually mounted on a support to which electrical connections lead and which, serving as the supporting base for the apparatus, is often utilized for housing the various electrical parts and/or amplifying elements. However, when this base is placed on a table, it is usually necessary to incline the latter in order that the optical axis of the apparatus may have the desired inclination.

Another shortcoming of existing supports is that replacement of a given apparatus involves replacement of the support and lengthy disassembling and reassembling operations.

The present invention aims to obviate these shortcomings by providing a novel supporting structure for apparatus of the type referred to, which permits replacing, for example, one projection apparatus by another, without disassembling and reassembling electrical connections, and tilting the optical axis at will without necessitating an inclined supporting table.

The supporting structure which is the object of the present invention, comprises, substantially, a cylindrically curved cradle mounted on a supporting base and on which is supported a slidably, matingly curved, shoe sole rigid with the lowermost end of the projector apparatus, said sole being adapted to be latched on the cradle in a position corresponding to the desired inclination of the optical axis. This sole is provided with elongated, parallel conductors insulated from one another and slidably contacted by resilient contacts located in said base and projecting through an aperture formed in the bottom wall of the cradle. Said conductors, connected within the shoe with the various wires leading from the projector apparatus, permit the shoe sole, and hence the entire apparatus, to be removed away from the cradle and replaced by another one, without disassembling and reassembling electrical connections between the projector apparatus and its supporting base.

The latter, which further serves to house, at least partly, electron-operated amplifying means or/and other electrical devices, may be easily placed on a horizontal table, or it may be rapidly mounted, for example, on a standard head with the aid of a clamp collar provided at the bottom of the supporting base.

Said electron-operated devices are secured on both sides of a plate located between the two halves of said supporting base, assembled by

2

means of bolts whose heads are embedded in elastic blocks to form feet which, by being acted upon manually, permit said halves and said plate to be disassembled with facility for revision and repair.

The invention will be more clearly understood by referring to the accompanying, more or less diagrammatic, drawings which illustrate, by way of example, an embodiment thereof and in which: 10 Fig. 1 is a longitudinal elevational view, in section, showing the supporting system according to the invention applied to a projection apparatus diagrammatically shown in the drawing;

Fig. 2 is a top plan view showing one half of 15 the supporting base of Fig. 1, as it appears after the removal of the projection apparatus, and a sectional plan view of the other half, showing clamping means for mounting the supporting base on a standard head; and

20 Fig. 3 is a sectional view of the supporting base, taken along the axis of the device for securing the projector sole to the cradle.

Similar numerals refer to similar parts throughout the several views.

25 Referring to the drawings, it will be seen that the upper portion of the supporting base 1 is formed with a cylindrically shaped depression 2 having its horizontal axis perpendicular to the vertical central plane thereof. This depression is limited, on each side, by vertical walls 3.

Machined against the walls 3 are two circular runways 4 serving to guide outstanding cylindrically shaped parts or skids 5, having the same radius as the runways 4, of a hollow shoe 6 rigid 35 with the lowermost end of the projection apparatus 7 diagrammatically indicated by dash-and-dot lines in Fig. 1, its optical axis being denoted by reference 8.

40 It is clear that because parts 5 of shoe 6 are slidably displaceable on the arcuate runways 4, the shoe 6 and projection apparatus 7 may tilt so that optical axis 8 may incline in one direction or the other.

The shoe 6 may be locked on the runways 4 45 by means of two angle-latches 9 vertically guided in housings provided on the outer faces of the walls 3. The latches 9 may be raised for unlocking, or they may be lowered to lock the shoe 6 against the supporting base 1.

50 The latches 9 are formed with horizontal coaxial round holes 12, and they are raised or lowered by means of two eccentrics 13, rigid with a shaft 14 passing through the holes 12 and journaled in the side walls 15 of the upper portion of base 1.

The shoe 6, and hence the projector 7, are locked or unlocked on the runways 4 by rotating the shaft 14 with the aid of a control handle 16.

At its lowermost end, the shoe 6 is provided with a layer of insulating material 17, arcuate in shape and concentric with, or even merging into, the slide surface of the circular skids 5.

Mounted in the insulating layer 17, flush with its lower surface, are conductive bars 18, parallel to one another and to the circular skids 5. These bars are conveniently connected to the various electric lines leading from the projection apparatus, for example from the sound producing device thereof.

Connections, by sliding contacts, with electron-operated devices, diagrammatically indicated by reference numerals 19 and 19', disposed on both sides of the insulating plate or plates 21, as well as with the electrical feed lines, are obtained by means of resilient contact-blades 22, each having one insulated end secured to an insulating bar 23 carried by the upper portion of the supporting base 1, while the free end thereof terminates in an inverted V projecting through an opening 24 formed in the arcuate bottom wall of the depression 2.

The contacts 22 provide also the desired contacts with the devices 19 and 19', these contacts being effected by means of resilient members 25 affixed to the plate 21, and held in contact with the returns 26 of contacts 22.

There is, therefore, no wire connection to be made between the apparatus 7 and the base 1, nor between the upper portion of this base and the electrical devices 19, 19' secured to the plate 21.

Side walls 27 and bottom wall 28 form the lower hollow portion of the supporting base, which portion is adapted to press the plate 21 against the lowermost edges of the upper portion of the base 1.

The three components of the base are assembled in the following way:

Bolts 29, passing through the bottom wall 28 and insulating plate 21, are screwed into bosses 31 rigid with the side walls of the upper portion of the base 1. Said bolts have their heads 32 embedded in blocks 33, of elastic material such as rubber, forming feet for conveniently placing the supporting base on a table (not shown). By manually turning the foot blocks 33, the bolts may be screwed up or down with great ease. They pass through spacer sleeves 34 located under the insulating plate 21 in such a way that the latter, and the dependent electrical and electron devices, may be set in convenient position, when the plate 21 is removed from the supporting base for revision or repair.

For mounting the supporting base on a tripod or standard head, the bottom wall 28 is provided with a clamp collar 35 having two clamping lugs 36 separated from each other by a variable distance 37. A screw 38, passing through the lugs 36 and turnable by means of a control handle 39, permits the collar to grip the tripod or standard head.

The collar 35 is made for example by being cast on the bottom wall 28, and its movability is obtained by extending its opening 41, formed in the said wall, through a portion of its outer periphery, as indicated by reference 42.

A cover 43, located over the collar 35, is affixed to the latter by means of screws 44 screwed into its body and passed with clearance through holes

made in the cover 43 to allow deformations of the collar 35.

If desired, the collar 35 may be inserted into the bottom wall 28, only a portion of the collar being secured to this wall to enable it to keep its elasticity.

It is clear that changes of detail may be made in the particular form of supporting structure, above described and shown, without departing from the spirit and scope of the invention.

It is also clear that the said supporting structure, capable of producing a desired inclination and electrical connection between a slidably arcuately shaped shoe sole and a corresponding stationary cradle supporting this shoe sole, may have application not only to motion picture projectors, but also to motion picture cameras, photographic apparatus, and even to certain electron-operated apparatus. Said shoe sole, which may be convex, for example, may be made integral with an apparatus, or it may be affixed to the lower end thereof.

What is claimed is:

1. A supporting structure for electrically operated motion picture apparatus and the like which comprises, in combination, an arcuately shaped cradle mounted on a hollow supporting base and adapted to support a matingly shaped shoe sole rigid with an apparatus to be supported, said shoe sole being slidably displaceable on said cradle, means for locking said shoe sole on said cradle in a position corresponding to the desired inclination of the optical axis of the apparatus, an insulating layer constituting said shoe sole, elongated, spaced, parallel conductive bars embedded in said layer, said bars being, on the one hand, connected within the shoe with the various electric wires leading from said electrically operated motion picture apparatus and, on the other hand, slidably contacted by resilient contacts located in said supporting base and projecting through an aperture formed in the bottom wall of said cradle, said arrangement of said conductive bars and contacts being such as to permit the shoe sole, and hence the apparatus itself, to be removed from the cradle and replaced by another apparatus, without disassembling and reassembling the connections between the apparatus and the supporting base, the latter including two superimposed, detachably interconnected, hollow components, a detachable plate located between said components for supporting various electrical elements housed in said two components and slidably engaging said conductive bars, means for assembling and disassembling, for revision or repair, said two components and said plate, and means for rapidly mounting the supporting base on a standard head.

2. Supporting system as defined in claim 1 in which the cradle is concave and the shoe sole convex.

3. Supporting system as defined in claim 1 in which the cradle is convex and the shoe sole concave.

4. Supporting system as defined in claim 1 wherein said means for locking said shoe sole on the cradle comprise two oppositely angled latches adapted to be lowered or raised, respectively, by means of two eccentrics rigid with a common, manually rotatable, shaft journaled in the respective side walls of the supporting base.

5. Supporting system as defined in claim 1 in which said assembling and disassembling means comprise bolts adapted to bolt together said two

components and plate of said base and having their heads embedded in blocks of elastic material in a manner to form feet for the base, while permitting rotation of the bolts.

6. Supporting system as defined in claim 1 in which said means for mounting the supporting base on a standard head comprise a clamp collar mounted on the bottom wall of the base in such a way as to cause said collar, through the medium of clamping lugs thereof, acted upon by a manually operated screw, to grip the standard head.

7. In an electrically operated photographic arrangement, in combination, a base member having a curved supporting surface portion thereon, said supporting surface portion being formed with an aperture passing therethrough; electrically conductive means located in said supporting surface portion and comprising a plurality of contact members consisting of electrically conductive material and extending through said aperture in said supporting surface portion; an electrically operated photographic apparatus resting on said base member and having a curved mounting surface portion located in contact with said supporting surface portion, whereby said photographic apparatus may be located in a number of positions on said supporting surface so as to permit the entire photographic apparatus to be tilted to a desired angle; and additional electrically conductive means comprising a plurality of elongated insulated bars of electrically conductive material mounted in said mounting surface portion and located only in abutting relation with said electrically conductive means located in said supporting surface portion, whereby said two electrically conductive means may be separated simply by raising said photographic apparatus from said base member.

8. In an electrically operated photographic arrangement, in combination, a base member having a curved supporting surface portion thereon, said supporting surface portion being formed with an aperture passing therethrough; electrically conductive means located in said supporting surface portion and comprising a plurality of contact members consisting of electrically conductive material and extending through said aperture in said supporting surface portion; an electrically operated photographic apparatus resting on said base member and having a curved mounting surface portion located in contact with said supporting surface portion, whereby said photographic apparatus may be located in a number of positions on said supporting surface so as to permit the entire photographic apparatus to be tilted to a desired angle; means for clamping said photographic apparatus on said supporting surface portion in a desired tilted position; and additional electrically conductive means comprising a plurality of elongated insulated bars of electrically conductive material mounted in said mounting surface portion and located only in abutting relation with said electrically conductive means located in said supporting surface portion, whereby said two electrically conductive means may be separated simply by raising said photographic apparatus from said base member.

9. In an electrically operated photographic arrangement, in combination, a base member having a curved supporting surface portion thereon, said supporting surface portion being formed with an aperture passing therethrough; electrically conductive means located in said supporting surface portion and comprising a plurality of con-

tact members consisting of electrically conductive material and extending through said aperture in said supporting surface portion; an electrically operated photographic apparatus resting on said base member and having a curved mounting surface portion located in contact with said supporting surface portion, whereby said photographic apparatus may be located in a number of positions on said supporting surface so as to permit the entire photographic apparatus to be tilted to a desired angle; means for clamping said photographic apparatus on said supporting surface portion in a desired tilted position; additional electrically conductive means comprising a plurality of elongated insulated bars of electrically conductive material mounted in said mounting surface portion and located only in abutting relation with said electrically conductive means located in said supporting surface portion, whereby said two electrically conductive means may be separated simply by raising said photographic apparatus from said base member; and electrical apparatus detachably mounted in said base member, said electrical apparatus being provided with electrically conductive means which is located only in abutting relation with said first-mentioned electrically conductive means located in said supporting surface portion, whereby, when said photographic apparatus is mounted on said supporting surface portion, it is in electrical communication with said electrical apparatus and whereby said electrical apparatus may be disconnected from said first-mentioned electrically conductive means in said supporting surface simply by removing said electrical apparatus from said base member.

10. In an electrically operated photographic device, in combination, a base member having a concavely curved supporting surface portion located thereon, said supporting surface portion being formed with an aperture extending therethrough; a plurality of electrically conductive brush members fixedly mounted in said base and having end portions which extend through said aperture in said supporting surface portion, said brushes being slightly spaced from each other; an electrically operated photographic apparatus mounted on said base member and having a convexly curved mounting surface portion comprising insulating material located in abutting relation with said concave supporting surface portion of said base member, said mounting surface portion of said photographic apparatus being connected at its sides to flanged convexly curved members which also rest on said supporting surface portion of said base member; a plurality of elongated electrically conductive bars mounted in said mounting surface portion of said photographic apparatus and located only in abutting relation with said brushes so as to conduct electricity from said base member to said photographic apparatus, said curved surface portions of said base member and photographic apparatus permitting the photographic apparatus to be tilted to a desired degree on said base member while maintaining electrical communication with said base member through said bars and brushes; and clamp means mounted on said base member and located in engagement with said flanged members for clamping said photographic apparatus to said base member in a desired angular position.

11. In an electrically operated photographic device, in combination, a base member having a concavely curved supporting surface portion lo-

cated thereon, said supporting surface portion being formed with an aperture extending therethrough; a plurality of electrically conductive brush members fixedly mounted in said base and having end portions which extend through said aperture in said supporting surface portion, said brushes being slightly spaced from each other; an electrically operated photographic apparatus mounted on said base member and having a convexly curved mounting surface portion comprising insulating material located in abutting relation with said concave supporting surface portion of said base member, said mounting surface portion of said photographic apparatus being connected at its sides to flanged convexly curved members which also rest on said supporting surface portion of said base member; and a plurality of elongated electrically conductive bars mounted in said mounting surface portion of said photographic apparatus and located only in abutting relation with said brushes so as to conduct electricity from said base member to said photographic apparatus, said curved surface portions of said base member and photographic apparatus permitting the photographic apparatus to be tilted to a desired degree on said base member while maintaining electrical communication with said base member through said bars and brushes.

12. In an electrically operated photographic arrangement, in combination, a base member having a curved supporting surface portion; an electrically operated photographic apparatus having a curved mounting surface portion located in contact with said curved supporting surface portion of said base member, whereby said photographic apparatus may be located in a number of positions on said supporting surface portion so as to permit the entire photographic apparatus to be tilted to a desired angle; first electrically conductive means located in said base and comprising a first set of contact members consisting of electrically conductive material and located in said supporting surface portion of said base member; and second electrically conductive means located in said electrically operated photographic apparatus and including a second set of contact

members consisting of electrically conductive material and located in said mounting surface portion of said photographic apparatus only in abutting relation with said first set of contact members in said supporting surface portion of said base member, whereby said two sets of contact members may be separated by raising said photographic apparatus from said base member.

13. In an electrically operated photographic arrangement, in combination, a base member having a curved supporting surface portion; an electrically operated photographic apparatus having a curved mounting surface portion located in contact with said curved supporting surface portion of said base member, whereby said photographic apparatus may be located in a number of positions on said supporting surface portion so as to permit the entire photographic apparatus to be tilted to a desired angle; first electrically conductive means located in said base and comprising a set of contact members consisting of electrically conductive material and located in said supporting surface portion of said base member; and second electrically conductive means located in said electrically operated photographic apparatus and including a set of elongated contact bars consisting of electrically conductive material and located in said mounting surface portion of said photographic apparatus only in abutting relation with said set of contact members in said supporting surface portion of said base member, whereby said sets of contact members and elongated contact bars may be separated by raising said photographic apparatus from said base member.
